UNITED STATES PATENT OFFICE.

HENRI CHIREIX, OF PARIS, FRANCE.

RECEIVING SYSTEM.

Application filed March 24, 1922. Serial No. 446,463.

To all whom it may concern:

Be it known that I, HENRI CHIREIX, a citizen of France, and a resident of Paris, France, have invented certain new and useful Improvements in Receiving Systems, of which the following is a specification accompanied by drawings.

The present invention relates to improvements in relays of the kind described 10 in my copending applications Serial Nos. 496,667 and 496,668, filed August 29, 1921, and more particularly to an improved adaptation of the said relay for automatic calling arrangements in wireless telegraphy or 15 telephony.

Generally speaking, the improvement effected by the present invention consists in the following: a vibrator system and a thermostat associated therewith for actuating a call indicating apparatus such as a bell is carried back to the circuit of the element that controls the oscillating conditions (comprising a three electrode tube arranged as a detector in accordance with the previous applications). The vibrator system is preferably arranged in a special manner by the combination of the two electro-magnetic relays.

The invention will be more clearly understood by reference to the single figure of the enclosed drawing which illustrates an embodiment of the invention. As shown, the arrangement comprises a three electrode tube 1, operating by appropriate circuits as a generator for maintaining oscillations in one or the other of the oscillating circuits 2 and 3, as described in said applications. Normally, the circuit 2 is oscillating, but this oscillating condition may be destroyed 40 and the circuit 3 set into oscillation due to the variations in the conditions of the circuit with which a coil 4 is associated, the coil being, for example, inductively connected with the circuit 2. As shown, this coil 4 is included in the plate circuit of a three electrode tube 5 arranged as a detector. This tube is actuated by the oscillations received through the coupling transformer 6, the primary terminals 7 and 8 50 of which are connected with the antenna of the station. In accordance with the present invention there is provided in series in the plate circuit of tube 5 the coil of relay 9 and a certain portion of an integrating device such as portion 10 of the resistance of a thermostat. The thermostat has

a contact 11 through which the call indicating apparatus 12 (bell, test lamp, etc.) is placed in a circuit. When the armature 13 of relay 9 engages the contact, the coil of relay 14 is connected in the battery circuit. When the armature 15 of this relay makes contact it shunts the portion 10 of the thermostat resistance and subjects the second portion 16 of the said resistance to the total potential of a common battery provided for heating the two tubes 1 and 5, for feeding the plate circuit of tube 5, for heating the thermostat, and for feeding the indicating apparatus 12. This battery is not shown in the drawing, and its positive and negative poles are connected to the similarly marked terminals of the circuits. A milliammeter 17 may be provided for regulating the circuit.

In order more clearly to explain the operation of the new arrangement it will be first assumed that the tube 1 does not operate and that no oscillations are received by the controlling tube 5. Under these conditions the relay 9 is traversed by a certain current. It will close the contact of its armature, whereupon the relay 14 becomes energized and the contact 15 is opened. The resistance 10 is now included in the circuit weakening the current. The contact 13 is opened, whereupon the contact 15 closes and the cycle of operation begins over again. The two relays 9 and 14 operate as a vibrator.

If we assume now that the tube 1 is energized and maintains the oscillating condition in the circuit 2 the coil 4, which is associated with this circuit will take up a certain energy, which produces circulation of rectified current in the circuit 4, 10, 9, 5; the apparatus is so constructed and adjusted that the intensity of this current is sufficient for holding the contact of relay 9 in closed position. Under these conditions, all of the heating resistance of the thermostat, i. e., the two portions 10 and 11 in series, are subjected to the potential U of the source connected to the terminals + and -.

As explained in the applications referred to, when a signal is received the circuit 3 oscillates instead of the circuit 2 due to the effect of coil 4. No more energy is then supplied to the coil 4 and the controlling circuit 4, 10, 9, 5. The relays 9 and 11 become deenergized and only the portion 16 of the

heating resistance of the thermostat is in the battery circuit. At the same time the oscillating order returns from circuit 3 to circuit 2. If at this time the signal still exists, 5 the same cycle is reproduced. For operating a call this is carried on in such a manner that during the reception of a signal the group of two relays is in vibrating condition and the energy transmitted into heat in the thermostatic oscillates between two values, one 10

$$\frac{U^2}{R_1 + R_2}$$

corresponding to the normal conditions and 15 the other

$$\frac{U^2}{R_1'}$$

in which R designates the resistance of portion 16 and R_2 the resistance of portion 10. The contact of the thermostat is adjusted in a manner such that a thermic balance is established so that the contact is made when the relays 9 and 14 are in normal condition 20 25 as a result of the energization of relay 9, and the thermic balance is not reached before this contact is made when the relay vibrates. The duration of the vibration, i. e., a duration that the signal must have 30 35 for causing the operation of the calling device 12, is adjustable by the spacing of the thermostat contact and depends also on the construction of this apparatus. It will be seen that these adjustments may be easily effected or the construction standard determined irrespective of the reception of a signal, simply by stopping the operation of the tube 1. Under normal conditions, if either tube is damaged the calling apparatus 40 45 will immediately give the signal as the relay 9 will then be deenergized.

Obviously, numerous modifications of the above described arrangement are possible without departing from the spirit of the 45 invention. The relays 9 and 15 may be of any suitable type that will perform the above described operation, or these relays may even be replaced by a single relay provided with suitable self-interrupting contacts. Furthermore, the thermostat or thermo-interrupter may perform other well known functions, only the division of its heating winding being a characteristic of the invention.

Having described my invention, what I claim is:

1. In signaling systems, a calling device, comprising a circuit adapted to oscillate, means responsive to signals adapted to control the oscillation of said circuit, a vibrator cooperating with said circuit and an integrating device having a portion adapted to be alternately utilized in response to the actuation of said vibrator to control an indicating device.

2. In signaling systems, a calling device comprising a circuit adapted to oscillate, means responsive to signals adapted to control the oscillation of said circuit, a vibrator cooperating with said circuit, an integrating device adapted to receive energy in different amounts in response to the actuation of said vibrator and an indicating device co-operating with the integrating device. 70

3. In signaling systems, a calling device comprising a pair of circuits adapted to oscillate, means responsive to signals adapted to cause one or the other of said circuits to oscillate, a vibrator cooperating with one of said circuits, an integrating device adapted to receive energy in different amounts in response to the actuation of said vibrator and an indicating device co-operating with the indicator. 75 80

4. In signaling systems, a calling device comprising a circuit adapted to oscillate, means responsive to signals adapted to control the oscillation of said circuit, a vibrator cooperating with said circuit, an integrating device cooperating with the vibrator and adapted thereby to alternately receive a normal and an abnormal energy input and an indicating device cooperating with the integrating device in response to the abnormal energy input. 90 95

5. In signaling systems, a calling device comprising a circuit adapted to oscillate, a receiving coil adapted to control the oscillation of said circuit and to receive energy from said circuit when it oscillates, a vibrator actuated in conjunction with said coil, a thermostat connected with the vibrator adapted to alternately receive increased energy and an indicator responsive to the increased energy of the integrating device. 100 105

6. In signaling systems, the combination of a pair of circuits adapted to oscillate, a receiving coil adapted to control the oscillation of said circuits and to receive energy from one of said circuits when it oscillates, 110 a vibratory relay in circuit with said coil and an integrating device cooperating with the relay adapted to receive increments of energy for operating a calling device.

7. In signaling systems, the combination of a pair of circuits adapted to oscillate, a receiving coil adapted to control the oscillation of said circuits and to receive energy from one of said circuits when it oscillates, 115 an integrating device, a current source, a vibratory relay having a coil connected to the receiving coil and an armature connected to the current source and adapted to connect the integrating device thereto for supplying energy for causing a desired operation. 120 125

8. In signaling systems, the combination of a pair of circuits adapted to oscillate, a receiving coil adapted to control the oscillation of said circuits and to receive energy 130

from one of said circuits when it oscillates, an integrating device, a current source, a vibrator comprising a pair of interconnected relays and an integrating device connected to the current source having a portion adapted to be alternately disconnected by said vibrator.

9. In signaling systems, a three electrode valve, a thermostat, a relay cooperating with said valve adapted to disconnect a portion of the heating coil of the thermostat and an indicating device cooperating with the thermostat.

10. In signaling systems, a three electrode valve, a thermostat having a divided heating coil, a relay cooperating with said valve, adapted to disconnect a portion of the heating coil of the thermostat and an indicating device cooperating with the thermostat.

11. In signaling systems, a three electrode valve, a thermostat having a divided heating coil, a relay having a coil in the plate circuit of the valve, said relay being adapted

to disconnect a portion of the heating coil of the thermostat to cause it to receive necessary operating energy and an indicating device cooperating with the thermostat. 25

12. In signaling systems, the combination of a three electrode tube having a pair of circuits in its output circuit adapted to oscillate, a second three electrode receiving tube, a coil in the output circuit of said receiving tube adapted to control the oscillation of said circuits in response to the received energy and to receive energy from one of said circuits when it oscillates, a relay coil in the circuit of said coil, a thermostat having a mid point of the heating coil connected to said coil and to the armature of a second relay, the armature of the first relay and coil 40 of the second relay being connected in series, said relay being adapted to cooperate to open circuit, a portion of the heating coil and an indicating device connected to the thermostat. 35

HENRI CHIREIX.
